W. B. CATER.

RAIL FITTING.

APPLICATION FILED JAN. 15, 1917.

1,326,182.

Patented Dec. 30, 1919.

Fig. 1.

Fig. 2.

This technical drawing illustrates a mechanical assembly. At the top, a stepped base (3) supports a vertical column (4). A horizontal beam (6) is attached to the right side of the column. The assembly features several numbered components: 1, 2, 5, 7, 12, 13, 15, 16, 17, 18, 19, and 20. Component 1 is at the top, 2 is on the left, 5 is at the bottom, 7 is on the right, 12 and 13 are on the right side of the horizontal beam, 15 is on the left side of the horizontal beam, 16 and 17 are on the right side of the horizontal beam, 18 is on the right side of the horizontal beam, 19 is on the left side of the horizontal beam, and 20 is at the bottom right.

UNITED STATES PATENT OFFICE.

WILLIAM B. CATER, OF NEW YORK, N. Y., ASSIGNOR TO JOHN SIMMONS COMPANY, OF NEW YORK, N. Y., A CORPORATION OF NEW YORK.

RAIL-FITTING.

1,326,182.

Specification of Letters Patent. Patented Dec. 30, 1919.

Application filed January 15, 1917. Serial No. 142,878.

To all whom it may concern:

Be it known that I, WILLIAM B. CATER, a citizen of the United States, residing at New York city, county of Kings, and State of New York, have invented certain new and useful Improvements in Rail-Fittings, fully described and represented in the following specification and the accompanying drawings, forming a part of the same.

This invention relates to certain improvements in rail fittings of that class in which rails are set up in position in posts or standards, as, for example, the guard rail constructions now widely employed in railway and subway construction.

It is the especial object of the present invention to provide an improved fitting for use in such constructions in which the rails and the standards or posts are locked together by a locking means which can be placed in the fitting after the rails are in position, and can be removed from the fitting while the rails are in position thereon, so that if it be necessary for any reason to replace such locking means, this can be done without disassembling the whole structure, and so that, furthermore, the locking means will not be displaced or lost when it is necessary to readjust or tighten the locking means after the structure has become settled by some extensive use.

It is a further object of the invention to provide an improved fitting for this purpose which shall be simple, and therefore cheap in construction, and which will be effective for long periods.

With these and other objects in view, a detailed description of the preferred constructions for effecting them, will be given in connection with the accompanying drawings, in which—

Figure 1 is a cross-section of a two-rail high structure, showing the improved fittings, the rail pipes and supporting post being broken away to save space;

Fig. 2 is an end view of the upper part of the construction shown in Fig. 1, and

Fig. 3 is an end view of the lower part of the construction shown in Fig. 1, part of the standard or post being shown broken away.

Referring now to these drawings, constructions embodying the invention will embody a sleeve or other similar tubular support through which the rail passes, such a

sleeve being marked 1. In constructions embodying the invention, this sleeve will be provided with a projection by which the fitting is attached in the structure. These attaching projections are marked 2, and in the preferred construction will be formed integrally with the sleeve 1. In the drawings is shown a sleeve having one attaching projection which is used for the upper rail, and a sleeve having the lower attaching projection 2 and an upper attaching projection 3, this latter sleeve being used for the middle or under-rails, where the rail structure is two or more rails high. The attaching projection 2 is threaded and has connected thereto a standard or post section 4 of pipe as is usual. The fitting employed for the middle or under-rails has the other end of the post or standard 4 threaded into the attaching projection 3, before referred to. This fitting has also an attaching projection 2 which supports another post section 5, the other end of which post section, where the structure is two-rail high, takes into a suitable post support, not shown.

The rails which are, as usual, of iron pipe, are marked 6 and are inserted in the sleeves and locked in position by locking wedges co-operating with the sleeves and acting to lock the pipe thereon. In accordance with the invention, these locking wedges are so shaped that the wedge locking key may be placed in position in the fitting and removed therefrom while the rail is in place. The wedge keys are, furthermore, so shaped as to have a large bearing surface against the pipe, and the locking key and the attaching projections are formed to give a large bearing surface for the other side of the locking keys. While the constructions for effecting this may be somewhat varied, a preferred form of key is that shown in Fig. 1, marked 7, this key 7 being provided with an end 12 having a wedge-shaped surface 13 and a long straight surface 14, a stem 15 extending from the head 12 and dropped downward slightly, as shown, and having a threaded end as shown at 15'. With a key of this character the attaching projection 2 is formed with a slot 16, the lower wall of which is beveled, as at 17, to co-operate with the wedge surface 13 of the key. This slot in the particular construction illustrated, extends through the attaching projection 2 and the wall 18 of the fit-

ting, this construction permitting the bearing surface 14 to be very long, and thus result in a very strong and rigid structure, and permits the key to be positioned in the fitting and removed therefrom while the rails are in position. In the best constructions the inner wall of the projection 2 at the point where the bottom of slot 16 is made, is formed thicker than the rest of the 10 wall, this being readily effected by casting a lug 19 at that point, this construction giving a substantial bearing surface at that point for the locking key. With a locking key as before described, the other side of 15 the projection 2 opposite the slot, is provided with a hole 20 through which the threaded end of the key is passed. Suitable means are provided for locking the keys in wedging position in the fitting and for taking up wear necessitated by settling of the 20 structure or other reasons. These means may be of various characters. A convenient one is a nut 21. Where the locking means is a nut, this nut will be preferably of brass 25 to prevent it from rusting fast to the stem, and will preferably be provided with a recess 22 for protecting a certain number of the threads at the threaded end of the key which can be used for tightening the wedge. 30 In assembling structures embodying the invention, a certain number of the posts, such as 3, are set up at suitable spaces and the pipes inserted in the fittings and the rails and posts trued up to proper position. The 35 locking keys are then put in place and tightened up to locking position. With the construction described, a very strong, rigid structure can be produced and one in which the locking keys can be inserted and removed 40 while the rails are in place, so that it is not necessary to disassemble the structure, where it is necessary to put in new keys, if they by any chance become lost or wear out. 45 While the invention has been shown and described in its preferred form, it will be understood that certain changes and variations may be made in it without departing from the invention. It will be understood, furthermore, that the fitting is capable of use 50 with structures other than railings of the class referred to, and may be and is intended for use in other relations.

What is claimed is:

1. In a rail fitting, the combination with a rail, of a sleeve through which the rail 55 passes, a wedge locking key, means for positioning the key in the sleeve and removing it therefrom while the rail is in position in the sleeve, and means for operating the key to lock the rail in the sleeve. 60

2. In a rail fitting, the combination with a rail of a sleeve through which the rail passes, an attaching projection on the sleeve having a slot open at the top through the thickness of the sleeve and projection, the 65 lower face of which is beveled, a wedge locking key formed to pass through the slot into the projection under the rail having a wedge face coöperating with the beveled face of the slot and a plain face taking 70 against the rail, a stem on the key passing through an opening in the projection, and means coöperating with the stem for locking the key in the projection.

3. In a rail fitting, the combination of a 75 sleeve through which the rail passes, an attaching projection on the sleeve having a slot extending through the wall of the sleeve and projection, the lower wall of the projection being beveled and formed with a 80 thickened portion having a similar bevel to provide a wide bearing surface, a wedge locking key formed to pass through the slot having a wedge face coöperating with the beveled face of the slot and the thickened 85 portion and a plain face taking against the rail, a stem on the key extending through an opening in the projection, and means on the stem for locking the key in position.

4. In a rail fitting, the combination with a rail, of a sleeve through which the rail passes, a wedge locking key having a stem, an opening at one side of the sleeve through which the stem may be passed, a slot open at the top through the thickness of the sleeve at 95 the opposite side of the sleeve said openings permitting the insertion and removal of the key when the rail is in position in the sleeve, and means for operating the key to lock the rail in the sleeve. 100

In testimony whereof, I have hereunto set my hand.

WILLIAM B. CATER.
